Patented Apr. 16, 1912.

UNITED STATES PATENT OFFICE.

EDWARD J. DUSTMAN, OF NEW YORK, N. Y.

OUTLET-BOX.

1,023,460.

Specification of Letters Patent. Patented Apr. 16, 1912.

Application filed December 6, 1909. Serial No. 531,490.

To all whom it may concern:

Be it known that I, EDWARD J. DUSTMAN, a citizen of the United States, residing in the city of New York, borough of Manhattan, in the county and State of New York, have invented a certain new and useful Improvement in Outlet-Boxes, of which the following is a specification.

The invention relates to outlet-boxes used in walls and partitions in electric lighting installations, and the object of the invention is to provide a simple and economically constructed box in which the cables may be easily entered and reliably secured without injury, and adapted for service with the usual gas pipe outlet, and which may be installed without undue damage to the wall or partition, or to the gas pipe by bending or otherwise straining the latter.

The invention consists in certain novel features and details of construction and arrangement by which the above objects are attained, to be hereinafter described.

The accompanying drawings form a part of this specification and show an approved form of the invention.

Figure 1 is a view of the front face of the outlet-box alone, as adapted for service with a gas fixture. Fig. 2 is a corresponding side view. Fig. 3 is a view of the rear face. Fig. 4 is a top view. Fig. 5 is a transverse central section taken on the line 5—5 in Fig. 1. Fig. 6 is a vertical section, partly in elevation, the plane of section being indicated by the line 6—6 in Fig. 1, showing the box in position in a wall and provided with an extension ring and canopy. Fig. 7 is a face view of the extension ring alone. Fig. 8 is a face view of the locking clamp. Fig. 9 is a corresponding edge view.

Similar letters of reference indicate the same parts in all the figures.

The box A is a circular casting in the form of a short cylinder having a deep vertical groove A¹ in the rear face, and a central opening A² leading therefrom to the front. On each side of the central opening is a deep transverse recess A³ communicating with the peripheral exterior of the box through vertical passages A⁴, one leading

upwardly from each recess and the other downwardly, on each side of the groove A¹ and parallel therewith.

In applying the box to a wall or partition having a gas outlet B¹, the plaster is cut away to admit the box and the latter inserted upon the gas pipe B which is received in and partially inclosed by the groove A¹, and with the gas outlet B¹ projecting through the central opening A², thus avoiding any necessity for removing the plaster along the line of the gas pipe to admit the latter to the box and also avoiding strains due to flexing the pipe in such admission, and the leaks caused by such strains. The box is held in place by screws extending through slots a a in the rear wall of the box, and these slots are so located and spaced as to coincide with the usual holes in the lugs B³ formed on the elbow or T-connection B² of the gas pipe, the screws thus inserted serving to hold both the box and pipe in position.

The cables D in the wall or partition are received in the vertical passages A⁴ which are of a diameter to admit their armored covering. The insulated wires inclosed therein extend through the reduced openings a⁴ between such passages and the recesses A³ and are easily bent forward in such recesses without strain on the cables. The positions of the passages A⁴ permit the cables D to enter the box without bending on short radii, thus greatly facilitating their introduction.

To afford the depth required in reaching through the lath and plaster of the wall, an extension ring E of the same diameter as the box and having internal lugs E¹ is secured to the outer or front face of the box by screws E² extending through the lugs and engaged in holes a¹ in the box. This ring projects beyond the surface of the wall and is inclosed by the rim or flange of an ornamental canopy J within which are the wires and the usual insulating joint F attached to the gas outlet B¹, serving to prevent contact of the wires with metal portions of the gas conduits. Angular spurs or lugs A⁵ on the margin of the central

opening A^2 receive screws H by which the box is anchored on the gas outlet.

Instead of pinching screws usually employed for the purpose, the cables are held 5 in the passages A^4 by yokes or clamps G lying in notches a^2 in the rear face of the box and having screw-threaded legs G^1 extending through the latter to the front where they receive nuts G^2 by which the 10 curved inner faces of the clamps may be drawn into close contact with the armor and thus hold the cables reliably gripped between the clamps and the opposite inner faces of the passages A^4 without danger of 15 piercing the armor and insulation of the cables.

In order to provide space for the clamps the walls of the passages A^4 are continued beyond the circular boundary of the box, as 20 at A^6 , and the notches a^2 are each cut at an angle therein so that the projections A^6 may be confined as nearly as possible to the general circular contour of the box.

Modifications may be made in the forms 25 and proportions as found necessary or desirable in conditioning the box for service in various situations to which it may be adapted.

I claim:—

30 1. An outlet box formed with a vertical groove in its rear face and having vertical passages for the reception of electric cables, and transverse recesses in the front face of the box between and communicating with 35 said passages for the reception of wires from said cables.

2. An outlet box formed with a vertical groove in its rear face and having vertical passages therein for the reception of electric 40 cables, and transverse recesses in the front face of the box between and communicating with said passages for the reception of wires from said cables, and centrally located means in said box for holding an 45 insulating joint.

3. An outlet box formed with a vertical groove in its rear face and having vertical passages therein for the reception of electric cables, and transversely arranged recesses in the front face of the box between 50 said passages for the reception of wires from said cables, and orifices of smaller diameter than said cables communicating between said passages and recesses.

55 4. An outlet box having a vertical groove in the rear face, constructed partially to inclose a gas pipe, and a central opening from said groove to receive a gas outlet from said pipe, vertical passages parallel with 60 said groove for the reception of electric cables, and transverse recesses in the front face for the reception of wires from said cables.

5. An outlet box having a vertical groove

in the rear face, constructed partially to inclose a gas pipe, recesses on each side of said groove constructed to receive lugs on said pipe, a central opening from said groove to receive a gas outlet from said pipe, vertical 65 passages parallel with said groove for the reception of electric cables, and transverse recesses in the front face for the reception of wires from said cables.

6. A cylindrical outlet box having a vertical groove in its rear face constructed 70 partially to inclose a gas pipe, a central opening from said groove to receive a gas outlet from said pipe, lugs on the margins of said opening and screws in said lugs for engaging said gas outlet, said box having 75 vertical passages for the reception of electric cables, and transverse recesses in the front face for the reception of wires from said cables, and an extension-ring 80 removably secured to said box.

85 7. An outlet box having passages therein for the reception of electric cables and having a notch in the rear wall of each of said passages, a clamp for each passage lying transversely of the latter in said notch and constructed to grasp such cable, a screw-threaded leg on said clamp extending through said box, and a nut on said leg engaged with the front face of said box.

8. An outlet box comprising a body having side and rear walls, said side walls being apertured for the reception of electric cables, the rear wall provided with a central longitudinal groove for the reception of a pipe, said groove opening into the interior 95 of the box through an aperture in the center of the rear wall and an inwardly extending hub surrounding said aperture.

9. An outlet box comprising a body having its rear wall provided with an opening 105 for a gas outlet and a longitudinal groove at an angle thereto for the reception of a pipe and means about said opening carrying securing means for affixing the outlet box to a pipe.

110 10. An outlet box comprising a body having its rear wall provided with an opening for a gas outlet and a longitudinal groove at an angle thereto for the reception of a pipe and means about said opening carrying 115 securing means for affixing the outlet box to a pipe, said body having an aperture for the reception of an electric cable.

11. An outlet box comprising a body having its rear wall provided with an opening 120 and means about said opening for affixing the box to a gas outlet, a groove to receive a pipe, said groove opening into the interior of the box through said rear wall and communicating with said opening, and an 125 extension ring on said box.

12. An outlet box comprising a body having side and rear walls, the rear wall pro-

vided with a central longitudinal groove for the reception of a pipe, said groove opening into the interior of the box through an aperture in the center of the rear wall, 5 and inwardly extending means surrounding said aperture and provided with means for affixing said box to a gas pipe.

In testimony that I claim the invention above set forth I affix my signature, in presence of two witnesses.

EDWARD J. DUSTMAN.
